UNITED STATES PATENT OFFICE

FLAY T. SERGENT, OF BELVIDERE, ILLINOIS

ROOF RAFTER

Application filed October 17, 1928. Serial No. 313,079.

This invention relates to roof rafters and more particularly to articles of this character adapted for use in the construction of relatively small buildings, such as poultry and hog houses.

5 One of the important objects of the present invention is to provide a rafter for supporting the roof of structures of this character in which the use of posts or other obstructing supports within the building are entirely eliminated.

10 A further object of the invention is to provide a rafter of this character of an arch shaped formation arranged with its lower ends adapted to provide an interlocking connection with the floor sill of the building, the rafter being further constructed in continuous formation whereby to eliminate the use of uprights in the construction of the building.

15 20 A further object of the invention is to provide a rafter of this character of a laminated construction.

25 Other objects and advantages reside in the special construction, combination and arrangement of the various elements forming the invention as more fully hereinafter described and claimed, reference being had to the accompanying drawings forming part 30 hereof, wherein like numerals refer to like parts throughout, and in which:

In the drawings:

35 Figure 1 is a view in elevation of one of the rafters looking through the arch formed thereby,

Figure 2 is an end elevational view of the inner edge of the rafter and

40 Figure 3 is a fragmentary group perspective of the interlocking ends of the rafter and the floor sill.

45 Referring now to the drawing in detail, the invention is illustrated as comprising a roof rafter indicated generally at 5 of laminated construction and composed of a series of relatively thin strips 6 secured to each

other in superposed relation as clearly illustrated in Figure 1 of the drawings whereby to permit the bending of the rafter in the form of an arch.

The strip 6 may be continuously formed, or 50 constructed of sections and when constructed in the manner last referred to, the abutting ends of the sections of the respective strips are disposed in staggered relation to prevent a weakening of the rafter at any particular 55 point throughout its length.

Also as clearly illustrated in Figures 1 and 3 of the drawings, the innermost and outermost strips have their ends 7 projecting beyond the ends of the intermediate strips. 60 By constructing the ends of the rafter in this manner, the ends 7 are adapted to fit within mortises 8 formed along the opposite side edges of the floor sill 9 of the building.

The inner face of the mortise 8 is inclined, 65 as shown at 10 along a plane corresponding to the curve of the projecting ends 7 of the rafter whereby to provide a snug fit therebetween. By providing an interlocking fit between the projected ends of the rafter and the 70 floor sill of the building, the use of fastening means between the rafter and the sill is eliminated.

After the rafters have been secured at spaced intervals along the sills 9 of the building, a suitable roofing may then be secured to the outer edges of the rafter. It will be apparent from the foregoing that by constructing a building in the manner indicated that the necessity of providing roof supports or 80 other obstructing frame work in the building is entirely eliminated.

After the strips have been bent to the desired shape and arranged in superposed relation, the same may be secured to each other 85 in any suitable manner, such as for instance, nailing or the like.

It is obvious that my invention is susceptible to various changes and modifications in construction without departing from the 90

spirit of the invention or the scope of the appended claim, and I accordingly claim all such forms of the device to which I am entitled.

Having thus described my invention, what I claim as new is:

A rafter for building construction comprising a series of superimposed strips, bent to a predetermined shape and secured to each other, the inner and outermost strips projecting beyond the ends of the intermediate strips, whereby to provide an attaching means for the ends of the rafter.

In testimony whereof I affix my signature.
